UNITED STATES PATENT OFFICE.

MARTIN M. JOHNSON, OF DAYTON, OHIO, ASSIGNOR OF ONE-HALF TO ALFRED L. VAN HORNE, OF DAYTON, OHIO.

BASE-BALL-GAME APPARATUS.

1,033,249.

Specification of Letters Patent. Patented July 23, 1912.

Application filed November 22, 1911. Serial No. 661,805.

To all whom it may concern:

Be it known that I, MARTIN M. JOHNSON, a citizen of the United States, residing at Dayton, in the county of Montgomery and 5 State of Ohio, have invented certain new and useful Improvements in Base-Ball-Game Apparatus, of which the following is a specification.

The present invention relates to games and 10 has particular reference to a mechanical baseball game apparatus.

An important object of the invention is to provide a mechanical contrivance of the above mentioned character, which may be 15 operated for playing the game of baseball in an exciting, fascinating, and realistic manner.

A further object of the invention is to provide a baseball game apparatus which 20 may be preferably played in accordance with the forms and rules employed in the professional baseball games.

A further object of the invention is to provide a device of the above mentioned 25 character, which is simple in construction, cheap to manufacture, and capable of being played with different degrees of success depending upon the skill of the operator.

Other objects and advantages of this invention will be apparent during the course 30 of the following description.

In the accompanying drawings forming a part of this specification and in which like numerals are employed to designate like parts throughout the same, Figure 1 is a plan view of the game apparatus as a whole, Fig. 2 is a vertical sectional view taken on the line 2-2 of Fig. 1, Fig. 3 is an enlarged fragmentary vertical sectional view taken 35 on line 3-3 of Fig. 1, Fig. 4 is a bottom plan view of Fig. 3, parts being omitted, Fig. 5 is a side elevation of a different form of batting element or disk, Fig. 6 is a rear side elevation of a stopping element for the 40 catcher, Fig. 7 is a plan view of the same, Fig. 8 is a plan view of a stopping element for any other player, Fig. 9 is a front elevation of the same, Fig. 10 is a plan view of a determining element or ring, Fig. 11 is a central vertical section through the same, Fig. 12 is a side elevation of a player member, and, Fig. 13 is a similar view of a bar magnet preferably employed in removing the ball from the pocket.

55 In the accompanying drawings in which

is illustrated a preferred embodiment of my invention, the numeral 1 designates a board constituting the field. This board is preferably surrounded by an upstanding flange or fence 2, attached thereto by suitable means. The upper surface of the board 1 is provided with spaced catching or holding means, preferably in the form of openings or pockets 3, disposed as shown. Formed upon the board 1 is a diamond 4, provided at its corners with home base 5, first base 6, second base 7, and third base 8. These bases are provided with the pockets or openings 3, as shown, preferably formed a little larger than the other openings 3. The numeral 9 designates the catcher's box. The numeral 10 designates the pitcher's box, having the pitcher's slab 11, as is customary. A path or track 12 connects the pitcher's box 10 and the home plate or base 5. It is to be understood that the upper surface of the board 1 is in the form of a flat plane and that the diamond 4 and the bases laid out thereon will not in any way interfere with this flat surface. The diamond and the bases may be 50 printed, painted, or otherwise indicated on the board 1 by any suitable means. The numeral 13 designates a left foul line and the numeral 14 designates a right foul line. Forwardly of the diamond 4 are spaced field 55 lines 15, 16, and 17, preferably shaped and arranged as shown.

The game is more advantageously played by two persons each of whom has a set of men, nine in number, as is customary in the ordinary game of baseball. Each of these men may preferably be collar-button shape, as shown in Fig. 12, wherein the numeral 18 designates the same. I do not wish to restrict myself, however, to any particular shape or design of the men, as the same may be widely varied without materially affecting the playing of the game. The collar-button shape of the men is advantageous inasmuch as it renders them convenient and easy to handle. The two sets of men are to be clearly distinguishable, and with this end in view said sets may be of different colors, that is one set may be painted red and the other set blue.

100 The batting apparatus comprises a vertically reciprocatory stem 19, operating through an opening 20 at the center of the home plate 5. Detachably connected with the upper end of the stem 19 by means of a 105

screw 21 is a batting element or disk 22, preferably frusto-conical in vertical cross-section. I have found that the best results are obtained by having the side wall of the 5 disk 22 inclined at an angle of about 50 to 60 degrees. Instead of employing the disk 22 I may remove the same and connect a second disk 23 with the stem 19. The disk 23 has its outer surface curved, as shown. 10 It is to be understood that the disk 23 is detachably connected with the stem in a like manner, as shown in connection with the disk 22. Formed upon the lower end of the stem 19 is a head 24, provided with a transverse 15 opening 25 formed therethrough for receiving an elastic band 26 or the like, the ends of which engage in grooves formed upon the lower ends of depending pegs 27, that are fixed to the board 1, as shown. It is thus 20 seen that the operator may quickly force the stem upwardly so that disk 22 will strike a ball 28 and when the stem is released the rubber band 26 will return said stem to its lowermost position, to bring disk 22 into engagement with the upper surface of the board 1. 25

The numerals 29, 30, 31, 32 and 33 designate stopping elements in the form, preferably, of curved strips or plates, as shown. 30 These stopping elements or plates are to be employed in connection with the infield players, each of which is provided with the same, except the pitcher. The catcher stopping element 29 is provided with a depending lug 34, to be inserted in one of the openings 3. Each of these stopping elements 35 may preferably have its inner face provided with a covering of felt 35 or like material. Attention is called to the fact that the element 29 is the only one of the stopping elements 40 employed in the infield which carries a depending lug 34 or other securing means. The numerals 36, 37 and 38 designate stopping elements, preferably in the form of curved strips or plates, which are 45 larger than the infield stopping elements and adapted to be used in connection with the fielders. Each of these stopping elements 36, 37 and 38 is preferably provided upon its inner face with a covering of felt 50 39 or like material.

In Figs. 10 and 11 I have shown what may be termed a determining element, preferably in the form of a ring 40. There are 55 preferably two of these rings, which are of different diameters, the smaller to be used in connection with the infielders and the larger with the outfielders, as will be further explained.

The playing ball 28 is preferably formed 60 of steel and in order that it may be quickly and easily removed from any of the pockets or openings 3, I provide a bar magnet 41, shown in Fig. 13.

In playing the game, the apparatus is operated as follows: Assuming that the red

men have the first inning at the bat, the blue men 18 will be placed at the bases and in the field in the ordinary positions, as shown. The player may shift his men as he deems best, by taking them out of certain openings 70 3 and placing them in other openings. In the infield the stopping elements 30, 31, 32 and 33 are placed in front of the first baseman, second baseman, short stop and third baseman, with their concave faces turned toward the home plate 5, as shown. These stopping elements preferably engage the upper ends of the men. The stopping element 29 is placed behind the home plate and surrounds the disk 22, as shown, the lug 34 of 80 said stopping element fitting in one of the openings 3. The stopping elements 36, 37 and 38 are placed in front of the fielders, in a corresponding manner. The board is placed on a table or other support so that the corners of the same project therebeyond, whereby the player may engage the head 24 of the stem 19 with his finger tip. The two persons playing the opposing teams sit opposite each other. The player of the out-field team now takes the ball 28 and rolls it toward the batting element 22. The rules may provide that the ball shall start to roll on or before passing the slab 11. By practice, the operator may roll the ball so it will curve and hence confuse the operator playing the batting element 22. As the ball approaches the batting element 22 the opposing operator quickly moves the stem 19 upwardly, to strike the ball with the element 22. If he fails to hit the ball after having three strikes, there will be one out for that side. If he strikes the ball and it rolls outwardly of either of the lines 13 and 14, it will be a foul or strike, in accordance with the well known baseball rules. If he hits the ball fair it may strike one of the holding elements in the infield or outfield or it may pass between them. If it passes these stopping elements and is caught in one of the 100 pockets 3 inwardly of the line 15, the man 18 makes a one base hit and is entitled to go to first base, if the ball is caught between lines 15 and 16, it is a two base hit, if caught between lines 16 and 17, there is a three 110 bagger, and if caught outwardly of line 17 or if the ball goes over the fence 2, there is a home run. Assuming that the ball has been struck and engaged by the stopping element 30 at first base and rebounds from the same and is then caught in one of the 120 openings 3 near such first base, to ascertain whether the man is out or not, the infield determining element 40 is placed about the first baseman 18, with said first baseman extending through the central opening thereof. If the opening within which the ball has been caught is in the radius of the element 40 or is covered thereby, the ball will be considered as having been caught by the 130

first baseman and hence the man at the bat will be out. Assuming that the ball has been again hit and goes to the left fielder, strikes against the holding element 38 therefore, and rebounds and is finally caught in one of the openings 3 inwardly of the line 15. The out field determining element 40 is now applied to this left fielder, above described, to ascertain if he has caught the ball. Assuming that the pocket holding the ball does not fall within the radius of the determining element, this will count as an error for the outfield team, and the ball being held inwardly of the line 15, the opposing team is entitled to a one base hit and the man will accordingly go to first base. Had this ball rebounded from the holding element and finally been caught by one of the pockets between lines 15 and 16, there would have been a two base hit, and if caught between lines 16 and 17, a three base hit, and so on. If the ball should be again batted fair and strike the holding element 31 of the second baseman and rebound from the same, into the holding element 32 of the short stop, and be caught by one of the pockets adjacent the holding element 32 so that said short stop would have been considered to have caught the ball as ascertained by the employment of the determining element 40, this would be an assist and would count as an out against the team at the bat. A man may steal from one base to another by the operator throwing such man 18 from the first base to the second, and if the man 18 is caught at the second base in the radius of the determining device 40, he is considered safe, and otherwise out. The successful operation of this practice requires considerable skill. After there have been three outs the red men take their proper positions in the field and at the bases and the board is turned around so that the other person may operate the batting element. The operation of the apparatus is then repeated.

I wish it understood that the form of my invention herewith shown and described is to be taken as a preferred example of the same and that certain changes in the shape, size, and arrangement of parts may be resorted to without departing from the spirit of the invention or the scope of the subjoined claims.

Having thus described my invention, I claim:—

1. In a game apparatus, a board having a diamond formed thereon, a stem movably mounted through the board, and a tapering disk attached to the stem.

2. In a game apparatus, a board, a taper-

ing disk disposed upon the upper surface of the board, and means to effect a vertical movement of such disk.

3. In a game apparatus, a board, a stem vertically movably mounted through the board, a tapering element attached to one end of the stem, and means to return said stem to its normal lower position when removed therefrom.

4. In a game apparatus, a board, and batting means including a vertically movable element extending through an opening in the board.

5. In a game apparatus, a board, having a diamond formed thereon and provided with a plurality of spaced pockets, a plurality of men to be disposed in positions on the board by being inserted in certain of the pockets, batting means, a ball, and a determining element to be placed adjacent the man to ascertain whether the pocket holding the caught ball is in the radius of said determining element, substantially as and for the purpose described.

6. In a game apparatus, a board provided with a plurality of pockets, a player element for insertion in one of the pockets, and a ring to be placed about said player element; substantially as and for the purpose specified.

7. In a game apparatus, a board provided with a plurality of holding means, and a determining element of a desired area to be placed adjacent a selected one of the holding means to ascertain what other holding means are at a certain distance from the selected holding means.

8. In a game apparatus, a board provided with a plurality of spaced pockets, a ball to travel on the board, a player element for insertion in one of said pockets, and a determining ring to be placed about the player element.

9. In a game apparatus, a board having a diamond formed thereon and provided with a plurality of pockets and having foul lines and field lines, batting means disposed at the home plate, a plurality of player elements for insertion in the openings near the bases and in the field, a plurality of stopping elements removably mounted near each player element, and a determining element in the form of a ring and adapted to be placed about a selected player element.

In testimony whereof I affix my signature in presence of two witnesses.

MARTIN M. JOHNSON.
